UNITED STATES PATENT OFFICE.

FREDERICK S. WOLSTENHOLME, OF RICHMOND, VIRGINIA.

BULLETIN BOARD.

Application filed January 3, 1927. Serial No. 158,670.

This invention relates to bulletin boards and more particularly to such a device adapted for use as a train bulletin in railroad stations and the like.

5 An important object of the invention is to provide a novel bulletin board having interchangeable signs whereby the time a train is due may be posted together with the time of its probable arrival.

10 A further object is to provide a bulletin board of the character referred to wherein the interchangeable signs and the supporting means therefor are of novel construction to permit the interchanging of signs to be

15 facilitated.

A further object is to provide a bulletin board having openings therein through which the interchangeable signs are visible, the signs being placed in position against

20 the back of the bulletin board and being held in position by novel supporting means.

A further object is to provide a bulletin board which is adapted to be operated wholly from the rear side thereof and provided with means for holding the interchangeable signs within the casing of the board when they are not in use.

A further object is to provide a bulletin board having a series of openings therein

30 through which the interchangeable signs are visible, each sign being provided adjacent its ends with rearwardly turned lips adapted to engage flanges of supports arranged against the rear face of the bulletin board.

35 A further object is to provide a bulletin board of the character just mentioned wherein the lips of the signs are provided with slightly curved rear edges which are adapted to engage against the flanges of the supports, the latter being flat and arranged angularly with respect to the bulletin board and forming therewith pockets to support the signs, the curved edges of the lips of the signs permitting the latter to assume positions flat against the rear face of the bulletin board to enhance the visibility of the signs.

40 A further object is to provide a bulletin board of the character mentioned wherein auxiliary signs may be employed for altering the reading of portions of the principal signs employed.

45 Other objects and advantages of the invention will become apparent during the course of the following description.

In the drawings I have shown one em-

bodiment of the invention. In this showing,

Figure 1 is a front elevation,

Figure 2 is a rear elevation,

Figure 3 is a detail perspective of an auxiliary sign,

Figure 4 is a vertical sectional view on line 4—4 of Figure 2,

Figure 5 is an enlarged vertical sectional view through a portion of the bulletin board proper and associated elements,

Figure 6 is a detail section on line 6—6 of Figure 2,

Figure 7 is a detail perspective of one of 70 the date signs,

Figure 8 is a fragmentary view of one of the principal signs, and,

Figure 9 is a similar view showing one of the signs and the means for supporting it. 75

Referring to the drawings the numeral 10 designates the bulletin board as a whole provided with a front wall 11 having a large opening therein in which is arranged the bulletin board proper as indicated at 12. 80 The board as a whole comprises a casing having a top wall 13, end walls 14 and a bottom wall 15. If desired, the board may be mounted upon casters or the like 16, or may be built into a wall. As clearly shown 85 in Figures 2 and 4, the rear of the board is entirely opened to provide access thereto whereby the board may be operated in a manner to be described.

The bulletin board proper may be provided at its top with suitable identification indicia 17 as shown in Figure 1, and below this indicia columns of openings 18, 19, 20 and 21 are provided, each column being provided thereabove with suitable indicia as 90 shown in Figure 1 to indicate the number of the train, the point from which it is traveling, the time when the train is due, and the time at which it is expected to arrive. A similar series of columns of openings are 95 arranged in the lower portions of the bulletin board proper to provide information as to when trains are due to leave, and their destinations. From a mechanical standpoint the two sets of columns are identical 100 and need not be referred to further in detail.

Adjacent each end wall 14, a vertical post or plate 22 is arranged, and this plate may be of any suitable form. A similar plate 23 is arranged between the columns of openings 19 and 20, as indicated in Figure 2. The plates 22 and 23 may be secured in

position in any suitable manner as by spot welding them against the bulletin board proper. Each face of the plate 23 and the inner faces of the plates 22 are provided with supports 24. These supports are identical in construction and only one need be referred to in detail. As clearly shown in Figures 5 and 9, each support is provided with a series of angular supporting flanges 25 which incline downwardly and forwardly toward their lower ends. These flanges may be stamped from the material of the supports and correspond in arrangement to the openings in the bulletin board proper. This arrangement of the flanges is clearly shown in Figures 4 and 5. While the supporting flanges 25 are shown as being formed of integral supports, it will be apparent that each of the supporting flanges may be separately formed and secured in position against the plates 22 and 23. As shown in Figure 2, single supports 25 are arranged at opposite ends of a separate opening 26 arranged near the top of the bulletin board, for a purpose to be described.

Interchangeable signs 27 are adapted to be arranged rearwardly of the openings in the bulletin board. Each of these signs is provided with a flat forward face upon which may be painted the desired information as to the destinations of the trains, etc., and each plate is further provided with an upper horizontal flange 28. Lips 29 are formed at the ends of the plates, and the rear edges of these lips are slightly curved as indicated at 30. These curved edges are adapted to engage against the flanges 25 as clearly shown in Figure 5. From this figure it will be apparent that the forward faces 27 are adapted to seat against the rear face of the bulletin board whereby the indicia on the sign will be visible through one of the bulletin board openings, and the curved edges of the lips 29 permits the sign to seat firmly against the bulletin board. One set of signs preferably is provided with indicia to indicate the destinations of the trains and also the numbers of the trains, the former indicia being visible through the openings 19 and the latter through the openings 18. Similarly another set of signs is provided with indicia to indicate the times at which trains are due to arrive, and each of these signs is preferably provided with identical indicia which is adapted to be viewed through an opening 21. Means are provided for altering the indicia to indicate the expected arrival of a train according to individual conditions.

As shown in Figure 8, the signs which indicate the times of arrival of trains may be provided on their upper horizontal flanges 28 with lugs 31. Auxiliary signs 32 are provided with forward faces having indicia thereon and upper horizontal flanges 33

bearing similar indicia. These signs are adapted to be placed in position with their forward faces arranged in front of the indicia of the main plates with which they are associated to indicate the expected arrival of trains, and each upper flange 33 is adapted to be arranged between adjacent pairs of the lugs 31. The plates 32 are adapted to bear any suitable indicia, as will be apparent.

In Figure 7 of the drawings I have shown a sign plate 34 which is adapted to be exhibited through the opening 26 to indicate current dates. As shown, the signs 34 are also provided with the end flanges 29 having curved rear edges 30, the latter being adapted to engage the supports 25 arranged rearwardly of the opening 26. The sign 34 is provided on its front face with spaced portions 35 and 36 to indicate the month and year, and a depression 37 is provided between these spaced portions to receive an auxiliary sign 38 bearing the number of the day. The auxiliary sign 38 also is provided with an upper horizontal flange 39 having indicia 40 thereon coinciding with the indicia on the front face whereby an operator may identify the plate while standing at the rear of the bulletin board. The plate 38 may be provided with a finger piece in the form of an upstanding flange 41 and also may be provided with an opening 42. All of the auxiliary signs, including the signs 32, may be provided with the finger pieces and openings 41 and 42 respectively.

The interior of the bulletin board 10 may be provided in its lower portion with inclined supports 43 to receive sign plates 27 when the latter are not in use. As indicated in Figure 2, each of the plates referred to may be provided on its rear face with indicia 44 indicating the number of the train, and an operator readily may read these numbers when sign plates not in use are arranged on the supports 43.

As shown in Figure 2, one of the end walls 14 may be provided with suitable hooks 45 adapted to be received in the openings 42 of the auxiliary signs whereby the latter may be supported within the board when not in use. The other end wall 14 may be provided with the hooks 45, if desired, as shown in Figure 4.

The operation of the device is as follows: One of the main sign plates 27 is arranged rearwardly of the uppermost openings 18 and 19, this plate bearing the destinations of one train together with its number, as indicated. Another of the plates is then arranged rearwardly of the corresponding openings 20 and 21 to indicate the time the train is due and the time at which it is expected to arrive. As previously stated, each of the time plates bears identical indicia at each end thereof for exhibition through the

openings 20 and 21, and such plate is used in its usual form if the train is expected on time. If the train is expected to be late, however, one of the auxiliary plates 32 may 5 be placed in position with its forward face between the face of the time plate and the rear face of the bulletin board. The lugs 31 are provided to properly position the auxiliary plates without the necessity of the 10 operator looking at the front of the board. One of the date plates is arranged rearwardly of the opening 26 according to the month and year, and such plate remains in position throughout the corresponding 15 month. It will be obvious that the day plates 38 may be changed from day to day by inserting the face of one of the plates in the recess 37.

Each of the main indicia plates, and the 20 date plate, is provided at opposite ends with one of the lips 29 having curved edges 30. When said plates are placed in position, the supporting flanges 25 serve not only to support the plates, but also move them inwardly 25 whereby they contact snugly with the rear face of the bulletin board proper. The curved edges of the flanges assist in this action, and the plates are adapted to snugly fit against the face of the bulletin board regardless of any slight irregularities in the 30 supporting flanges 25. The main indicia plates, when not in use, are arranged in the supports 43, and the numbers of the trains on the rear faces of the indicia plates are 35 clearly visible to the operator to permit him to select the proper plates for display. The finger pieces 41 of the auxiliary plates facilitate the placing of these plates, while it will be apparent that they conveniently may 40 be hung on the hooks 45 when they are not in use. The main indicia plates readily may be placed in position and removed by grasping the horizontal flanges at the upper edges thereof.

45 It will be obvious that the hooks 45 may be placed in any convenient position to render the auxiliary plates readily accessible. For instance, the hooks may be provided on the inner faces of both end walls 14 and 50 also against the inner face of the forward wall of the casing as indicated in the upper left hand corner of Figure 2.

It is to be understood that the form of the invention herewith shown and described is to 55 be taken as a preferred example of the same and that various changes in the shape, size and arrangement of parts may be resorted to without departing from the spirit of the invention or the scope of the subjoined claims.

30 I claim:

1. A device of the character described comprising a board having an opening therein, a pair of supports fixed with respect to and having faces inclined downwardly toward said board and arranged ad-

jacent opposite ends of said opening, and a sign plate adapted to be arranged against one face of said board to be visible through said opening, each end of said plate being provided with a projecting lip engaging 70 one of said inclined faces.

2. A device of the character described comprising a board having an opening therein, a pair of supporting flanges fixed with respect to and arranged rearwardly of said board adjacent opposite ends of said opening, said supporting flanges being inclined downwardly toward said board, and a sign plate arranged rearwardly of said board 75 against said opening to be visible therethrough, said plate being provided at opposite ends with rearwardly projecting lips 80 engaging said supporting flanges.

3. A device of the character described comprising a board having an opening therein, 85 a pair of supporting flanges fixed with respect to and arranged rearwardly of said board adjacent opposite ends of said opening, said supporting flanges being inclined downwardly toward said board, and a sign plate arranged rearwardly of said board against said opening to be visible therethrough, said plate being provided at opposite ends with rearwardly projecting lips 90 having their rear edges curved and contacting with said flanges.

4. A device of the character described comprising a board having an opening therein, a pair of supporting flanges fixed with respect to and arranged rearwardly of said board adjacent opposite ends of said opening and inclined downwardly toward said board, and a sign plate arranged rearwardly of said board and against the rear face thereof adjacent said opening to be visible therethrough, said plate being provided at opposite ends with rearwardly projecting lips, 100 each of said lips contacting with one of said flanges substantially at a single point.

5. A device of the character described comprising a board having a plurality of parallel horizontal openings, vertical supports fixed with respect to said board and arranged adjacent opposite ends of said openings, each of said supports being provided 110 with a supporting flange corresponding in position to each of said openings and inclined downwardly toward said board, and a sign plate adapted to be arranged rearwardly of any of said openings against the rear face of said board and provided at its ends with rearwardly projecting lips contacting with the corresponding flanges.

6. A device constructed in accordance with claim 5 wherein said lips are provided with curved rearward edges adapted to contact with said flanges.

7. A device of the character described comprising a board having an opening therein, a pair of supports fixed with respect to and 120

- 4
- having faces inclined downwardly toward said board and arranged adjacent opposite ends of said openings, a sign plate adapted to be arranged against one face of said board to be visible through said opening, each end of said plate being provided with a projecting lip engaging one of said inclined faces, and an auxiliary sign plate having a face provided with indicia and arranged between and contacting with said first named sign plate and said board and supported by said first named sign plate.
  - 8. A device of the character described comprising a board having an opening there-in, a pair of supporting flanges fixed with re-

spect to said board and arranged adjacent opposite ends of said opening and inclined downwardly toward said board, a sign plate having indicia thereon and provided at opposite ends with rearwardly projecting lips, 20 said plate being arranged rearwardly of said opening and contacting with the rear face of said board with said lips contacting with said supporting flanges, and an auxiliary sign having indicia thereon and arranged 25 between and contacting with said board and said sign plate.

In testimony whereof I affix my signature.

FREDERICK S. WOLSTENHOLME.
